CLAIM

The ornamental design for a surface ornamentation for flatware, as shown and described.

DESCRIPTION

FIG. 1 is a perspective view of a surface ornamentation for flatware showing my new design;

FIG. 2 is a front elevational view thereof;

FIG. 3 is a perspective view of a second item of flatware showing my new design;

FIG. 4 is a front elevational view thereof;

FIG. 5 is a perspective view of a third item of flatware showing my new design;

FIG. 6 is a front elevational view thereof;

FIG. 7 is a perspective view of a fourth item of flatware showing my new design;

FIG. 8 is a front elevational view thereof; and,

FIG. 9 is an enlarged perspective view of a representative portion, shown in detail callout of FIG. 1.

The broken lines shown in the drawings are for illustrative purposes only and form no part of the claimed design.
